UNITED STATES PATENT OFFICE.

WILLIAM E. SHARP, OF CHICAGO, ILLINOIS, ASSIGNOR, BY DIRECT AND MESNE ASSIGNMENTS, TO ALCOHOL HEATING & LIGHTING COMPANY, OF CHICAGO, ILLINOIS, A CORPORATION OF DELAWARE.

BURNER.

1,101,099.

Specification of Letters Patent. Patented June 23, 1914.

Application filed July 16, 1910. Serial No. 572,335

To all whom it may concern:

Be it known that I, WILLIAM E. SHARP, a citizen of the United States, residing at Chicago, in the county of Cook and State of Illinois, have invented certain new and useful Improvements in Burners, of which the following is a specification.

My invention relates to improvements in burners, and refers particularly to burners used for regulating the temperature of freight cars for the storage of vegetables and the like.

In the case of freight cars which are artificially heated, it is necessary that the proper temperature should be maintained in the car with a minimum amount of attention on the part of the train operator. At the same time it is essential that there should be no danger of the car taking fire from the heating device which is employed. In order to accomplish these results, I employ a burner which preferably uses alcohol as a fuel, the alcohol flowing from a reservoir into a vaporizing tube through which passes a rod of invar or other suitable metal having a low coefficient of expansion. When the vaporizing tube is heated, it expands, thereby unseating a valve seat which is connected with the vaporizing tube, and which is normally seated against a ball on the end of the rod passing through the tube.

After passing through the vaporizing tube, the vapor next passes through a needle valve which may be regulated to give the desired flow of vapor. From this valve the vapor flows through a pipe having an aperture therein and finally passes through an air space to the burner. The function of this air space is to supply oxygen to the vapor so that complete combustion of the flame is thereby attained on the same principle by which a Bunsen burner operates.

A suitable pan is provided beneath the vaporizing tube to effect the preliminary heating of the same, but after the burner has attained its normal operation, part of the flame coming from the burner of the heater is directed against the vaporizing tube, and thereby serves to keep the same hot. It will now be apparent that if the flame accidentally becomes extinguished, the vaporizing tube will contract, thereby closing the ball valve and cutting off the flow of liquid fuel to the vaporizing tube.

These and other advantages of my invention will be more apparent by reference to the accompanying drawings in which:

Figure 1 is a side elevation of my improved burner, part of which is shown in longitudinal section. Fig. 2 is an enlarged vertical section on the line 2-2 of Fig. 1. Fig. 3 is a fragmentary plan and partly horizontal sectional view of the burner, the vaporizing tube and the needle valve. Fig. 4 is a fragmentary bottom plan and partly horizontal sectional view on the line 4-4 of Fig. 1.

The fuel reservoir 11 is connected, by means of feed pipe 12, with a ball valve 13, which is in turn connected with the end 70 of a vaporizing tube 14 by means of suitable screw threads. The valve 13 is provided with a valve seat 15 which is adapted to engage the ball 16, mounted on the end of the rod 17 which passes through the vaporizing tube 14. The opposite end of the rod 17 is screw threaded, and connected with the block 18 which is clamped between the flange 19 on the end of the vaporizing tube 14 and the flange 20 on the end of the needle valve casing 21. The rod 17 is preferably made of invar or some similar metal which has a very low coefficient of expansion. It will now be apparent that if the vaporizing tube 14 is expanded by heat, it will carry the valve seat 15 to the right as shown in Fig. 1, thereby allowing liquid fuel to flow from the pipe 12 to the vaporizing tube 14. As most clearly shown in Fig. 2, the rod 17 is preferably surrounded with a plurality of small rods or wires 22, so that the rod 17 is kept centered within the vaporizing tube 14, while at the same time a greater surface of liquid fuel is exposed to the vaporizing action, as will be explained in detail hereafter.

Within the valve casing 21 is the valve stem 23 having a threaded portion 24 which engages corresponding threads within the valve casing 21 and has at its end the handle 25, by means of which the valve stem 23 may be rotated. It will be apparent that by such rotation, the beveled end of the valve stem 23 may be moved to the desired distance from its valve seat 26. Communicating with the inside of valve casing 21 is the port 27 which passes through the end of the rod 17 and leads to the annular space be-

tween the rod 17 and the inside of the vaporizing tube 14.

The valve casing 21 has a downward extension 28 in the form of a pipe which is closed by the plug 29. In the side of the pipe 28 is an aperture 30, opposite to the open end of pipe 31, leading to the burner 32. The burner 32 is provided with a top 33 in which are a plurality of holes 34 which 10 communicate with the inside of the burner 32. As most clearly shown in Fig. 4, the top 33, which has a diameter considerably in excess of the main portion of the burner 32, is provided with supplementary apertures 35 15 which are directed toward the vaporizing tube 14. Fastened to the bottom of the burner 32, by means of the screw 36, is the pan 37.

The operation of my burner may now be 20 readily understood. When the burner and the vaporizing tube 14 are cold, as when the burner is not in operation, the valve seat 15 is seated against the ball 16 so that liquid fuel, which is introduced into the reservoir 25 11, cannot pass beyond the ball 16. In order to start the burner, liquid fuel, such as alcohol, is placed in the pan 37 and lighted, thereby heating the vaporizing tube 14 and causing the same to expand, and moving the 30 valve seat 14 away from the ball 16. Fuel from the reservoir 11 now flows into the vaporizing tube 14, and since the latter has become heated, the fuel is vaporized. The vapor passes through the port 27 into the 35 valve casing 21 at a rate which is regulated by means of the valve stem 23. The vapor then passes outwardly through the pipe 28 and through the aperture 30. This vapor next passes into the open end of pipe 31 40 having entrained a considerable amount of air in its passage from the aperture 30 to the pipe 31; this mixed vapor and air then passes through the pipe 31 to the burner 32 and then through the holes 33 and 35. The 45 vapor is lighted after it passes through these holes. It will now be apparent that the vaporizing tube 14 is kept heated by means of the flame which results from the vapor passing through the holes 35, and thus the

valve seat 15 is kept separated from the ball 16, and at the same time the liquid fuel passing from the vaporizing tube is volatilized. If the flame from the burner 32 is extinguished, by accident or otherwise, the vaporizing tube will contract, and the flow of fuel 5 from the reservoir 11 will be cut off, thereby preventing waste of fuel and danger of causing the car to catch fire.

What I claim is:

1. A burner having an expansible vaporizing tube, a valve casing carried by the inlet end of the tube, a valve stem carried by and within the tube, a valve carried by the stem and located within the casing, the stem being provided with an outlet port communicating with the interior of the vaporizing tube, and a vapor regulating outlet valve for said port, substantially as described.

2. A burner including a burner body, an expansible vaporizing tube extending through and projecting at opposite sides of the burner body, a valve casing carried by the inlet end of the tube, a valve stem carried by and within the tube, a valve carried by one end of the stem and located within the casing, the opposite end of the stem being provided with an outlet port, a vapor-regulating outlet valve for said port, and a conduit communication from the port to the burner body, substantially as described.

3. A burner having an expansible vaporizing tube, a valve casing carried by the inlet end of the tube, a valve stem within and projecting at opposite ends of the tube, a valve carried by one end of the stem and located in the casing, an external block provided upon the other end of the stem exterior of the tube, said end of the stem having an outlet port therein, and an outlet valve casing for said port, said valve casing being connected to the expansible tube and clamping the valve stem block between the tube and the casing, substantially as described.

WILLIAM E. SHARP.
